(57) **CLAIM**

The ornamental design for an cosmetic container, as shown and described.

DESCRIPTION

FIG. 1 is a Perspective view of a cosmetic container showing my new design;

FIG. 2 is a Front elevational view thereof;

FIG. 3 is a Right elevational view thereof;

FIG. 4 is a Left side view thereof;

FIG. 5 is a Rear side view thereof;

FIG. 6 is a Top plan view thereof; and,

FIG. 7 is a Bottom plan view thereof.

The broken lines in the drawing depict portions of the cosmetic container that form no part of the claimed design.

1 Claim, 7 Drawing Sheets
